CLAIM

The ornamental design for a combination telephone handset and its stand with loud speaker, as shown and described.

DESCRIPTION

FIG. 1 is a left side, top and front perspective view of a combination telephone handset and its stand with loud speaker showing my new design;

FIG. 2 is a left side elevational view thereof, the side opposite being substantially a mirror image thereof;

FIG. 3 is a rear elevational view thereof; and,

FIG. 4 is a bottom plan view thereof.

The showing of cords in fragmentary form is for ease of

illustration.

FIG. 1

FIG. 2

FIG. 3

FIG. 4
